HENRY B. PETIT, OF DETROIT, MICHIGAN, ASSIGNOR TO GEORGE M. HOLLEY, OF DETROIT, MICHIGAN

HOT SPOT MANIFOLD

Application filed May 27, 1927, Serial No. 194,667. Renewed May 22, 1930.

This invention relates to a hot spot manifold adapted to be used with an internal combustion engine having external vaporizing means.

5 The specific object of this invention is to combine in one manifold an adjustable hot spot with a fuel vaporizing device, the effectiveness of which is not varied.

Figure 1 shows an elevation, with the float 10 chamber removed.

Figure 2 shows a partial section on plane 2-2 of Figure 1.

Figure 3 shows a section on the plane 3-3 of Figure 1, said plane being inclined from 15 the normal in order better to illustrate the invention.

In the figures, A is the exhaust manifold, having four exhaust entrances located at O¹, O², O³, O⁴. B is the inlet manifold. C is the 20 hot spot provided in the inlet manifold at the point where the incoming mixture divides into two horizontal streams and also where the exhaust gases from all the cylinders are united in one stream by the partition L. In 25 Figure 3 the exhaust entrance O₂ corresponds to both O₂ and O₃ which discharge on either side of the throttle D. D is a valve in the exhaust manifold controlled by a lever E, which in one position directs this united 30 stream of exhaust gases against the hot spot C, and in another position, shown in broken lines in Figure 3, diverts the stream of exhaust gases away from the hot spot C.

Z is a fuel vaporizing means consisting of 35 a hollow cover for an opening in the exhaust manifold A, corresponding to the vaporizing elements 45 44 in the Welch Patent #1547474, or to the elements 31, 32, 33 of the Welch Patent #1562670. The fuel is fed to this vaporizing element Z from the float chamber F, and 40 a small quantity of air is admitted through the passage G from the main air entrance N which communicates with G through the pipe P. The purpose of admitting this primary air is to entrain the fuel and facilitate vaporization. In Figure 1 the float chamber F is removed so that the fuel entrance G can 45 be seen. The details of the float and nozzle construction are not shown.

50 H is the outlet from the vaporizing element

located in the cover Z. The vapor flows through the passage I to the throat of the Venturi tube J which forms the mixing chamber and which is supplied with air from the air entrance N which communicates with the atmosphere, where the vaporized fuel is diluted with the cold air, the mixture thus formed flows through the mixture outlet past the throttle K into the inlet manifold B. The exhaust gases united in one stream are 55 passed through a passage controlled by a valve D (lever E) and delivered over the vaporizing element located in the cover E. The exhaust gases finally discharge through 60 the exhaust outlet M.

Operation.—The exhaust enters the manifold from O¹, O², O³, O⁴, and is united by the partition L into one stream, which, by means of the valve D (in the position illustrated), is diverted against the hot spot C, whence it 65 flows down to M, sweeping enroute over the fuel vaporizing device located within the cover E. When the valve D is in the horizontal position, shown in broken lines in Figure 3, the exhaust entering at O¹, O², O³, O⁴, 70 flows directly against the fuel vaporizing device E, and so to the exhaust outlet M, avoiding the hot spot C. It is obvious therefore, that the exhaust gases flow at all times over the fuel vaporizing device E, but on the other 75 hand, the hot spot C is only operative when the exhaust valve D is in the vertical position. Very effective means for controlling the mixture temperature in B is thus provided, which is the object of this invention. 80

In cold weather when the maximum heat is desired, any fuel which flows through E H I to the mixing chamber J and past the throttle valve K and is not thereupon vaporized is deposited upon the hot spot C, where it 85 is vaporized and from which it flows down B into the inlet ports of the engine. The area of the hot spot C, of course, is larger than indicated on the drawing, as common to the inlet and exhaust manifolds, for the reason that the walls of the inlet manifold B conduct heat and therefore the entire wetted area of the inlet manifold B serves to absorb heat from the exhaust manifold A, provided the valve 90 D is in the vertical position. The result is 95

that the wetter the mixture the larger the effective area of the hot spot C, and the dryer the mixture the less effective is this hot spot, which is one reason this hot spot gives the 8 results it does.

When the valve D is in the horizontal position, the exhaust space between D and C forms an ante-chamber which serves as a heat insulator preventing heat passing to C from 10 O. The operator is thus able to control the mixture temperature, or rather to compensate for variations in atmospheric temperature, as the desired result is that the mixture temperature should be kept between certain 15 permissible limits, namely between 160° F. and 200° F. when operating with kerosene, and between 110° F. and 140° F. when operating with gasoline.

What I claim is:—

20 1. A vaporizer, comprising an exhaust manifold, an outlet therefrom, an opening therein adjacent said outlet, a cover therefor, a vaporizing element located in said cover, means for admitting fuel to said element, an 25 inlet manifold located above said exhaust manifold, a mixing chamber discharging into said inlet manifold, a passage connecting said vaporizing element with said mixing chamber, a wall common to said inlet and exhaust 30 manifolds, a partition in said exhaust manifold adapted to unite all the exhaust gas into one stream, a valve in said exhaust manifold, said valve being located so as to cooperate with said partition so as to direct all 35 the exhaust gases against the said hot spot when in one position, and, in another position, to divert all the exhaust gases away from said hot spot, but in neither position to interfere with the free flow of the exhaust 40 gases over said vaporizing element.

2. A vaporizer comprising an inlet manifold, an exhaust manifold, an outlet therefrom, a partition in said exhaust manifold serving to concentrate all the exhaust gases 45 in the exhaust manifold at a point intermediate between the entrance and the exit, a heated wall in said inlet manifold forming also the wall of the exhaust manifold, located where the exhaust gases are concentrated into 50 one stream, a mixture chamber discharging an explosive mixture to said inlet manifold directly against said hot spot.

3. A vaporizer comprising an inlet manifold, an exhaust manifold having an outlet, 55 a moveable partition in said exhaust manifold at an intermediate point in said exhaust manifold, a heated wall in said inlet manifold forming also the wall in the exhaust manifold so located that the shunted exhaust gases 60 are directed thereon and thereover, a mixture chamber discharging an explosive mixture directly against said hot spot.

4. A vaporizer comprising an inlet manifold, an exhaust manifold having an outlet, a 65 moveable partition in said exhaust serving in

one position to shunt the exhaust gases in the exhaust manifold at an intermediate point in said exhaust manifold, and in another position to isolate the hot spot from the stream of exhaust gases, a heated wall in said inlet manifold forming also the wall in the exhaust manifold located where the shunted exhaust gases will impinge thereon and thereover, a mixture chamber discharging an explosive mixture directly against said hot 70 spot. 75

5. A vaporizer, comprising an inlet manifold an exhaust manifold, an outlet therefrom, a moveable partition in said exhaust manifold serving to concentrate the exhaust 80 gases in the exhaust manifold at a point intermediate between the entrance and the exit to any desired degree, a heated wall in said inlet manifold forming also the wall of the exhaust manifold, located where the exhaust 85 gases are so concentrated so as to impinge on said hot wall in said inlet manifold, a mixture chamber discharging an explosive mixture to said inlet manifold directly against 90 said hot spot.

6. An inlet manifold, an exhaust manifold, a common wall there between, a moveable partition in said exhaust manifold, so located that in one position said exhaust gases are thrown against said common wall, and in another the common wall is isolated from the exhaust gases by means of a complete stoppage of the exhaust gases.

In testimony whereof I affix my signature.

HENRY B. PETIT.
